(57) **CLAIM**

The ornamental design for a lighting fixture as shown and described.

DESCRIPTION

This application is related to commonly assigned, co-filed U.S. design patent application Ser. No. 29/791,176, filed on Jan. 3, 2022, by Daniel A. Montecino and Andrew M. Schuyler, entitled "Lighting Fixture", which application is incorporated herein by reference in its entirety.

FIG. 1 is a front perspective view from below of a lighting fixture according to the new design;

FIG. 2 is a rear perspective view from above thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is an enlarged bottom plan view thereof.

The broken lines in the drawings illustrate portions of the environment and the lighting fixture and form no part of the claimed design.

The long dash-short dash lines in the drawings represent a boundary of the claimed design and form no part of the claimed design.
